CLAIM

The ornamental design for a car, toy car or car replica as shown and described.

DESCRIPTION

FIG. 1 is a front perspective view of a first embodiment of the car, toy car or car replica showing our design;
FIG. 2 is a rear perspective view thereof;
FIG. 3 is a front elevation view thereof;
FIG. 4 is a right-side view thereof, with the opposite side view being a mirror image;
FIG. 5 is a rear elevation view thereof;
FIG. 6 is a top plan view thereof;
FIG. 7 is a front perspective view of a second embodiment of the car, toy car or car replica showing our design;
FIG. 8 is a rear perspective view thereof;
FIG. 9 is a front elevation view thereof;
FIG. 10 is a right-side view thereof, with the opposite side view being a mirror image;
FIG. 11 is a rear elevation view thereof; and,
FIG. 12 is a top plan view thereof.
Portions of the car, toy car or car replica shown in broken lines and de-emphasized mesh areas of the car, toy car or car replica form no part of the claimed design.

1 Claim, 12 Drawing Sheets
